W. SEVERN.

SPRING ACTUATED PIVOTAL CONNECTING MEANS FOR MOP HANDLES.
APPLICATION FILED JAN. 12, 1914.

1,100,029.

Patented June 16, 1914.

UNITED STATES PATENT OFFICE.

WILLIAM SEVERNS, OF CHICAGO, ILLINOIS.

SPRING-ACTUATED PIVOTAL CONNECTING MEANS FOR MOP-HANDLES.

1,100,029.

Specification of Letters Patent. Patented June 16, 1914.

Application filed January 12, 1914. Serial No. 811,636.

To all whom it may concern:

Be it known that I, WILLIAM SEVERNS, a citizen of the United States, residing at Chicago, in the county of Cook and State of Illinois, have invented certain new and useful Improvements in Spring-Actuated Pivotal Connecting Means for Mop-Handles, of which the following is a specification.

My invention relates to improvements in mops, preferably those known as polish mops, adapted for use in dusting, polishing and oiling, and has particular reference to apparatus of this character embodying yielding means pivotally connecting the handle and head of the mop, whereby the mop will be self adjusting in use.

An important object of the invention is to provide a mop of the above mentioned character, which is simple in construction, inexpensive to manufacture, durable, and convenient in use.

A further object of the invention is to provide spring actuated pivotal connecting means between the mop head and handle, whereby the handle may be shifted to any desired angular position with relation to the mop head, the spring means automatically returning the mop head to its normal position with relation to the handle upon the removal of pressure from the mop head.

A further object of the invention is to provide spring actuated pivotal connecting means between the handle and mop head, the same embodying an elastic element or elements which engage with a portion of the mop head, holding the same against improper turning movement with relation to its supporting frame.

Other objects and advantages of this invention will be apparent during the course of the following description.

In the accompanying drawings forming a part of this specification and in which like numerals are employed to designate like parts throughout the same, Figure 1 is a plan view of a mop embodying my invention, Fig. 2 is a side elevation of the same, Fig. 3 is a longitudinal sectional view taken on line 3-3 of Fig. 2, and Fig. 4 is a transverse sectional view taken on line 4-4 of Fig. 1.

In the drawings, wherein for the purpose of illustration is shown a preferred embodiment of my invention, the numeral 5 designates a mop head as a whole, which is preferably triangular, as shown. This mop

head comprises a tubular portion 6, from which depends a layer or layers of absorbent material 7, preferably formed of cord. The tubular portion 6 is preferably triangular, for receiving a triangular or angular supporting frame 8, preferably formed of a strip of metal, bent into a triangular shape. Owing to the fact that the strip 8 constituting the supporting frame is arranged upon its edge, and since the same has a substantial vertical width, it is obvious that the supporting frame will be rigid with respect to bending in the vertical plane. The strip 8 is provided at its ends with extensions 9, which are spaced and parallel, as shown.

The numeral 10 designates a tubular socket, receiving therein a handle 11. At its inner end this tubular socket is provided with oppositely arranged converging arms 12, preferably formed integral therewith. These arms are provided at their free ends with extensions or heads 13, engaging each other in parallel relation, and arranged between the extensions 9, as shown. The heads or extensions 13 are provided adjacent the free ends of the arms 12 with laterally extending stop lugs 13', adapted for engagement with cam faces 14', formed upon the free ends of the extensions 9, whereby the downward movement of the socket 10 with relation to the mop head 5 will be limited when lugs 13' engage cam faces 14'. The extensions 9 and 13 are provided with openings 14, in registration with each other, for receiving a transverse pivot element, in this instance, shown as a bolt 15. Arranged upon opposite sides of the extensions 9 are headed spacing sleeves 16, surrounding the pivot element 15, as shown.

The numeral 17 designates suitably stiff coil springs, arranged upon the spacing sleeves 16, as shown. Corresponding ends of these coil springs are extended outwardly in the form of spring arms 18, having their free ends bent downwardly for providing hooks or lateral extensions 19, fitting within the space between the converging arms 12. The opposite corresponding ends of the coil springs 17 are extended in the form of spring arms 20, having their free ends bent to form loops or inverted substantially U-shaped elements 21, which straddle the end portions of the tubular portion 6 of the mop head, the same having firm clamping engagement therewith, whereby these free ends of the tubular portion of the mop head can-

not turn or partake of other improper movements with relation to the frame 8.

In the use of my improved mop, the mop head is placed in engagement with the floor or the like to be cleaned, polished, or oiled, and the handle 11 may be moved to any desired angular position with relation thereto for convenient manipulation of the mop. It is obvious that the yielding pivotal connection between the mop head and handle is of such a construction that the same is entirely self-adjusting, whereby there is no necessity of the operator soiling the fingers by manipulation of parts of this connection. In my present construction the handle is freely pivotally connected with the mop head frame to be swung with relation thereto, the spring or springs serving to oppose this movement in one direction, with an increased force as the swinging movement in the same direction is continued.

It is to be understood that the form of my invention herewith shown and described is to be taken as a preferred example of the same, and that various changes in the shape, size and arrangement of parts may be re-

sorted to without departing from the spirit of the invention or the scope of the subjoined claim.

Having described the invention, what I claim is:—

The combination with a mop head supporting frame provided with apertured extensions, of a handle attaching element having apertured extensions arranged adjacent the first named apertured extensions, a pivot element passing through the apertured extensions, and springs arranged upon opposite sides of the apertured extensions, having portions thereof coiled about and engaging the pivot element, corresponding ends engaging the handle attaching element, and the opposite corresponding ends provided with approximately U-shaped loops adapted to receive portions of the mop head and have clamping engagement therewith.

In testimony whereof I affix my signature in presence of two witnesses.

WILLIAM SEVERNS.
